[57] CLAIM

The ornamental design for a tumbler or the like, substantially as shown.

DESCRIPTION

FIG. 1 is a top perspective view of the tumbler or the like showing my new design;

FIG. 2 is a side elevational view thereof;

FIG. 3 is a top plan view thereof;

FIG. 4 is a bottom plan view thereof; and,

FIG. 5 is a cross-sectional view thereof taken along line 5—5 of FIG. 3.
